[57] CLAIM

The ornamental design for the roller conditioner implement, as shown and described.

DESCRIPTION

FIG. 1 is a perspective view of the roller conditioner implement of this invention;

FIG. 2 is a top plan view thereof, the tillage crossbar to which this implement attaches being shown in phantom line;

FIG. 3 is a bottom plan view;

FIG. 4 is a left side view, showing the implement slightly elevated; and,

FIG. 5 is a left side view of the roller conditioner implement of this invention applied to the surface of the ground.

The broken line showing is for illustrative purposes only, and forms no part of the claimed design.
